Primary Examiner — Darlington Ly(74) *Attorney, Agent, or Firm* — Harrington & Harrington; Curtis L. Harrington(57) **CLAIM**

The ornamental design for a vehicle mud flap as shown and described.

DESCRIPTION

FIG. 1 is an upper left perspective view of a vehicle mud flap showing my new design, a mirror image thereof, is claimed but not shown;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 bottom plan view thereof.

The broken lines illustrate and surround portions of the vehicle mud flap which form no part of the claimed design.

1 Claim, 3 Drawing Sheets(56)
